US00D916130S

(12) **United States Design Patent** (10) **Patent No.:** **US D916,130 S**
Kim et al. (45) **Date of Patent:** **** Apr. 13, 2021**

(54) **DISPLAY SCREEN OR PORTION THEREOF WITH GRAPHICAL USER INTERFACE**

(71) Applicant: **Samsung Electronics Co., Ltd.**, Suwon-si (KR)

(72) Inventors: **Sooah Kim**, Seoul (KR); **Youngsu Park**, Seoul (KR)

(73) Assignee: **Samsung Electronics Co., Ltd.**, Suwon-si (KR)

(**) Term: **15 Years**

(21) Appl. No.: **29/690,565**

(22) Filed: **May 9, 2019**

(30) **Foreign Application Priority Data**

Nov. 13, 2018 (KR) 30-2018-0052362

(57) **CLAIM**

We claim the ornamental design for a display screen or portion thereof with graphical user interface, as shown and described.

DESCRIPTION

FIG. 1 is a front view of a first embodiment for a display screen or portion thereof with graphical user interface showing our new design; and,

FIG. 2 is a front view of a second embodiment thereof. The outermost broken lines showing the display screen or portion thereof form no part of the claimed design. The remaining broken lines in the figures depict portions of the graphical user interface that form no part of the claimed design.

1 Claim, 2 Drawing Sheets
